PURSE CONSTRUCTION

Charles H. Seaver, Los Angeles, Calif.

Application March 11, 1957, Serial No. 645,232

3 Claims. (Cl. 150—28)

This invention relates to a purse, handbag and similar structures and has for an object to provide such a structure that is particularly convenient to use because of a sectional compartmental arrangement.

Another object of the invention is to provide a purse construction that includes a plurality of compartments and is so made that access may be had to any compartment without opening or in any way disturbing the others.

A further object is to provide a purse construction as above in which a single closure means is provided for all of the sections and which, when released, enables opening of any one of the several compartments of the construction.

A still further object of the invention is to provide a purse structure formed of external interfitting compartment sections and a common releasable closure for said sections.

A yet further object of the invention is to provide a self-locking closure in a purse structure of the character above referred to.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes, one embodiment of the present invention, which is given by way of illustration or example only.

In the drawing, like reference characters designate similar parts in the several views.

Fig. 1 is a perspective view of a purse construction, showing the same closed, and formed according to the present invention.

Fig. 2 is an enlarged elevational view, partly in vertical section, showing the purse construction in one of several open positions.

Fig. 3 is a further enlarged elevational view, in quarter section, of a self-locking release means used in the present construction.

Fig. 4 is a fragmentary detail view showing a separable connection means that may be used in the present invention.

The present purse construction comprises a lower section 5, an upper section 6, similar intermediate sections 7, and a common closure 8 for said sections, and means 9 to releasably lock the closure means 8.

The sections 5, 6 and 7 may be made of any rigid material and are advantageously made of a plastic that may or may not be transparent. In any case, the sections are preferably thin-walled and light in weight. The lower section 5 is preferably provided with a bottom wall 10 and an encircling cylindrical wall 11 that constitutes a cuff that, together with the bottom wall 10, defines a top-open compartment 12.

The upper section 6, in a somewhat similar manner comprises a top wall 13 and an encircling cylindrical wall 14 that depends from the wall 13 and forms a bottom-open compartment 15. The thickness of wall 14 is made 5 to be somewhat greater than that of wall 11. Therefore, while the outer faces of walls 11 and 14 are the same in size and configuration, the inner face of wall 14 defines a smaller compartment 15 than the compartment 12. A skirt wall 16 extends downwardly from the thicker wall 10, 14, the same being of an outer size to telescopically fit into the lower section 5 so that compartments 12 and 15 combine to form a single larger compartment. A shoulder 17 where skirt wall 16 starts engages the upper edge of wall 11 to limit the positional relationship of the sections 15 5 and 6.

Each section 7 comprises a bottom wall 18, a cylindrical wall 19 encircling wall 18 and of a thickness similar to the thickness of wall 14, an upper flange or skirt wall 20, and a lower flange or skirt wall 21. One of the walls 20 or 21 (in this case, the wall 21) is similar to wall 16 in that the same extends from the inner side of wall 19 and defines a position-limiting outer shoulder 22. The other of said flange or skirt walls (in this case, the wall 20) extends from the outer side of wall 19 and defines a 25 position-limiting inner shoulder 23. It will be understood that the bottom wall 18 may have any suitable position between the upper and lower edges of each section 7.

From the foregoing, it will be clear that in the same way that skirt wall 16 may fit into wall 11, the same may fit within wall 20 of an adjacent section 7. Also, the skirt wall 21 may fit within wall 11 or within wall 20. Therefore, so long as the top and bottom sections are used, the purse may include several intermediate sections 7, only one section 7 or none at all. Depending on the number 35 of sections used, the purse will have one compartment less than the number used, the compartments being defined between the bottom and top walls 10 and 13 and the walls 18 of the intermediate sections.

When a complement of sections 5, 6 and 7 are interfitting, as desired, any two of them may be separated as shown in Fig. 2 to give access to the interior of the compartment that is enclosed by said sections. Such separation may be effected without disturbing the other sections and their compartments.

45 The closure 8 for the sections above described, preferably comprises two sets of tubes or sleeves 24 on the opposite sides of each section, substantially in the manner shown. The openings in the sleeves 24 extend, as shown more clearly in Fig. 2, through the side walls of the sections from the shoulders at the bottom adjacent the depending skirt wall 16 upward to the top of the upper flange or skirt wall 20. In order to insure ready alignment of said tubes, the sections 5, 6 and 7 are made to be non-round, for instance, oval, as shown. Thus, the tubes on each side 55 align to form continuous passages 25.

Said closure 8 further includes a pair of flexible elongated members 26 that may comprise cords, straps, thongs, etc., the same freely extending through the continuous passages 25, thereby wholly enclosing the portions of the cords or the like alongside the interfitting sections. Protection so afforded the flexible elongated members 26 of the frame thereof obviates snagging when the purse or handbag is carried by the owner, so that it cannot catch on projecting objects when the owner carries the handbag. The appearance of the handbag is also enhanced, and the tubular members 24 act as handles to aid the owner in lining up the sections when they are assembled. One end of each member 26 is provided with an enlargement 27, of any suitable form and incapable of entering passages 25. Thus, the members may extend upwardly in 65 said passages and outwardly from the upper end of section 5. It will be clear that the purse sections may be 70

held in assembly enclosing the compartments thereof by drawing the free ends of the members 26 together across the top of the top section 6, substantially as shown. By opening or spreading said free ends, any two of the sections may be separated, as described.

The releasable lock 9 (shown in detail in Fig. 3) normally seeks a locked position gripping the members 26. Said lock may be in the form of a conventional clutch slide. As illustrated it comprises telescopic housing members 23 and 29 that are longitudinally spread, as by a spring 30, the member 29 being formed to house a collet or similar tapered elements 31 that are urged into gripping engagement with the member 26 by a tapered seat 32 in housing member 29 when spring 30 is free to exert its force. Thus, the flexible members 26 are gripped, as indicated. By pressing on opposite ends of lock 9 to move the housing members together against the spring bias, the members 26 are released because the bias on the collet is removed. By pushing against the face 33 housing member 29, the lock may be slid along members 26 while the free ends of the latter are being held. Thus, the lock may be automatically set in section-locking position. When the opposite ends of the lock are pressed together, as described above, the flexible members are released and can be loosened. In fact, the lock 9 may be entirely removed from member 26 to enable such rearrangement of the purse sections, as may be desired. It is to be understood, however, that the invention is not limited to the employment of the particular type clutch illustrated.

In order to hold the adjacent sections separably connected when the means 3 is loosened, a bayonet slot 40 in the skirt wall 21 of one section may be engaged by a pin 41 in the skirt wall 20 of an adjacent section. The connection shown being a rotational one, the sections are preferably round. If the section walls are suitably flexible, the connection may be used in non-round sections.

While the foregoing has illustrated and described what is now contemplated to be the best mode of carrying out my invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. A handbag comprising a plurality of telescopically interfitting sections one above another enclosing separate compartments one less in number than the number of sections, said sections including a top section, a bottom section and interchangeable intermediate sections, and flexible cord means retaining connection of the sections and serving to hold the same separably in interfitting engagement, each section above the bottom section having

a depending skirt wall recessed from the lateral outer surface of the section to form a shoulder, each intermediate section having a lateral wall with an upwardly extending flange adapted to fit and surround the skirt wall of the section above and engage the shoulder thereof to produce a smooth unbroken lateral surface of the assembly of sections when in interfitting relation, each of the sections including cord-protecting guides on each side wholly enclosing the cord means alongside the sections, aiding and guiding the sections into interfitting relationship when assembled, the tops of the different sections being aligned when the sections are interfitting to define continuous passages, said flexible cord means comprising elongated members arranged over the top and along the opposite sides of the handbag and extending through said passages.

2. A handbag comprising a plurality of interfitting sections one above another enclosing separate compartments, one less in number than the number of sections, said sections including top and bottom sections to form a top and bottom respectively of the handbag and an intermediate section, and flexible cord means retaining connection of the sections and serving to hold the same separably in interfitting engagement each section above the bottom section having a depending skirt wall recessed from the lateral outer surface of the section to form a shoulder, each section below the top section having a lateral wall with an upwardly extending flange adapted to fit and surround the skirt wall of the section above and engage the shoulder thereof to produce a smooth unbroken lateral surface of the assembly of sections when in interfitting relation, each of the sections including cord protecting guides on each side aligned with a guide of the adjacent section wholly enclosing the cord means alongside the sections, aiding and guiding the sections into interfitting relationship when assembled, the tops of the different sections being aligned when the sections are interfitting to define continuous passageways, said flexible cord means extending through said passageways.

3. A purse as in claim 2 in which the adjacent sections are formed with bayonet joints for separable connection having connected positions when the passageways are aligned whereby the flexible cord means may be passed through the passageways to lock the bayonet joints.
